JOHN P. KING, OF PROVIDENCE, RHODE ISLAND, ASSIGNOR TO WALLING & WALLING, OF PROVIDENCE, RHODE ISLAND, A FIRM COMPOSED OF EVERETT L. WALLING AND LESTER S. WALLING

STOP MOTION FOR DRESSING MACHINES

Application filed June 15, 1928, Serial No. 285,758. Renewed June 27, 1930.

This invention relates to improvements in stop-motions, more particularly adapted for use in thread-dressing machines. The general type of dressing machine shown and described herein is claimed in a separate application filed by me on even date herewith.

An object of the invention is to provide a stop-motion for thread-dressing machines wherein a detector arranged to be actuated by an imperfection in the thread causes the thread feeding mechanism to become inoperative.

Another object is to provide means for automatically disconnecting the thread feeding mechanism from the driving mechanism when an imperfection is detected in the thread.

Another object is to produce an efficient, strong and durable stop-motion for thread-dressing machines, which is simple in construction and inexpensive to manufacture.

With these and other objects in view, the invention consists of certain novel features of construction, as will be more fully described, and particularly pointed out in the appended claims.

The views of the drawings are as follows:—

Figure 1 is a plan of a thread-dressing machine, constructed according to the invention, the stop-motion mechanism being shown in normal operative position.

Figure 2 is a view partly in elevation and partly in section showing diagrammatically the mode of dressing the thread in the machine shown in Figure 1.

Figure 3 is an enlarged view of the stop-motion mechanism shown in Figure 2;.

Figure 4 is a section taken on the line 4—4 of Figure 1 showing diagrammatically the mode of taking the thread from the supply package;

Figure 5 is a vertical section through the eye in the end of the detector arm;

Figure 6 is a horizontal section through the thread feeding mechanism showing a stop-motion partly in plan and partly in section.

Figure 7 is a vertical section taken on the line 7—7 of Figure 6; and

Figure 8 is a view, partly in section and partly in elevation, as seen from the line 8—8 of Figure 6.

It is of advantage in the manufacture of threads, and the like to provide the machines used for dressing and finishing the threads with means for automatically stopping the mechanism when imperfections are detected in the threads, so that such imperfections can be removed before the threads are finished and rewound; and it is also of advantage to so construct and arrange the stop-motion mechanism that the several portions of the dressing machines simultaneously and automatically stopped through the actuation of a single element; and the following is a description of one construction by which these advantageous results may be accomplished:—

Referring to the drawings, a thread dressing machine equipped with my invention is shown as including a frame composed of side bars 11 and 12, and end bars 13 and 14, arranged rectangularly in the manner shown in Figure 1, to best receive and support the several parts of the machine, as will be hereinafter more fully described.

The end bar 13 of the frame has a pair of brackets 15 and 16 fixed thereto and extending inwardly therefrom. These brackets are adapted to receive a spindle 17 on which is revolvably mounted a spool 18 containing the thread 19 to be dressed and otherwise finished in the machine.

The brackets 15 and 16 are extended to provide upright arms 20 which support a cross-bar 21, over which the thread 19 passes. As shown, the bar 21 should be disposed above, and slightly in advance of the spool 18.

The bracket 16 has an arm 22 pivotally connected thereto, as indicated at 23. This arm is extended to a point in front of the spool 18, and carries a roller 24. The thread is passed, in the form of a loop 25, under the roller 24 and over the cross-bar 21. In this way the roller 24 and the arm 22 will be supported by the loop 25 and the weight of the roller and arm tends to tighten the loop and draw the same downwardly. For the purpose of limiting the downward swinging movement of the roller 24, the inner end of the arm 22 is provided with a foot 26 adapted to engage a set-screw 27 threaded through the bracket 16.

For the purpose of retarding the rotation of the spool 18, as well as the delivery of the thread therefrom, one end of the spool has a circular disk 28 fixed thereto. This disk 5 may be positioned on the end of the spool adjacent to the arm 22, and such disk is partially encircled by a band 29. One end of the band is fixed to the arm 22, as indicated at 30, while the opposite end of the band is secured to a fixed portion of the machine, as indicated at 31.

The tension of the thread being unwound from the spool 18 is such that, during the 10 operation of the machine, the roller 24 will be lifted sufficiently by the loop to relieve the pressure of the band 29 on the disk so that the spool will be free to rotate at a speed substantially equal to the speed at which the thread is travelling through the machine.

20 However, as soon as the speed of the thread is retarded the loop 25 will lengthen, thereby permitting the roller 24 to fall sufficiently to draw the band 29 into engagement with the periphery of the disk, and thus retard the rotation of the spool so as to prevent the 25 thread from being delivered from the spool faster than the same is drawn through the machine. In this way, overrunning of the 30 spool is prevented and the thread will be delivered therefrom at a speed equivalent to the speed at which the thread travels through the machine.

It will also be understood, that should the 35 thread break after leaving the spool, the tension of the thread in the loop 25 will be released, thereby permitting the arm 22 to swing downwardly on its pivot whereby the band 29 will be applied to the periphery of the disk with sufficient force to immediately 40 prevent further rotation of the spool.

In this way a simple and effective brake 45 has been provided for controlling the delivery of the thread from the spool, and, as will be hereinafter fully described, mechanism is provided for automatically actuating this braking means, as well as for automatically stopping the machine, when any imperfections are detected in the thread.

The thread is immersed in a suitable liquid 50 solution contained in a tank 32 located in the bottom of the machine. The thread may be guided through the tank by a pair of spaced wheels 33.

The sides of the tank may be enclosed by 55 a jacket 34 containing water having a temperature suitable for maintaining the liquid solution in the tank 32 at the desired temperature. In order to remove excess liquid from the thread as it emerges from the tank, the 60 thread passes through a wiper 35 of any approved construction.

In the particular type of machine herein 65 shown the thread, after it has been immersed in the solution, is passed a number of times around a pair of spaced drums 36 and 37,

each drum having a multiplicity of grooves 38, so as to guide the thread and separate the loops.

The drum 36 is mounted on a shaft 39 journalled in bearings 40 and 41, the former being fixed to the side bar 11, while the latter is fixed to the side bar 12 of the frame. One end of the shaft 39 carries a gear 42 which meshes with a gear 43 on a drive shaft 44 supported by a bracket 45 mounted on the side 75 bar 12. The shaft 44 also carries a pulley 46, which may be connected to an electric motor, or other suitable source of power (not shown) by means of a belt 47.

The drum 37 has a spindle 48, and when 80 the drum 36 is revolved, the drum 37 will also be revolved by the travelling thread which is propelled by the drum 36, the loops of the thread serving as means for transmitting the power from the drum 36 to 85 the drum 37, as will be readily understood.

The drums 36 and 37 preferably should be of the same diameter and have the same number of grooves 38, and the thread, which is first passed over the drum 36, is then looped 90 around the drum 37 and returned to the drum 36, this looping of the thread around the drums continuing until a multiplicity of loops are formed. In this way a considerable 95 length of thread will be exposed to the atmosphere between the two drums, thus permitting some of the solution to evaporate before the thread is further treated.

The thread is led from the drum 36 upward to a drum 50 at the top of a dryer 51, the 100 drum 50 also being of substantially the same diameter as the drums 36 and 37 and having a plurality of grooves for receiving the thread.

The dryer 51 comprises an elongated body, 105 preferably formed from sheet metal and having an open top to permit the escape of the heat, and its bottom connected to a pipe 52 containing a heating element 53, of any approved type.

The circulation of the heat through the 110 dryer may be effected through a blower unit 54, of any desired type.

Near the bottom of the dryer there is another grooved drum 55, similar in construction to the drum 50. The thread is passed around the drums 50 and 55 a multiplicity of times, and is then led from the drum 50 to a spool 56 on the end of the machine opposite to the spool 18.

For the purpose of moving the thread through the dryer 51 and also for the purpose of reducing the elasticity in the thread, the drums 50 and 55 are adapted to be rotated at a speed slightly faster than the speed of 125 the drums 36 and 37.

In the present instance I have employed a direct drive from the drum 36 to the drum 55, such drive comprising a gear 57 mounted on one end of the drum 36. The gear 57 130

meshes with an idler gear 58 revolvably mounted in a bracket 59 fixed to the side bar 12, and the gear 58 meshes with a gear 60 fixed to the spindle 61 of the drum 55.

The gear 60 is provided with fewer teeth than the gear 57, and the construction and arrangement of the parts should be such that the drums 36 and 55 are both rotated in the same direction with the speed of the drum 55 slightly faster than that of the drum 36 so that the thread will be moved faster around the drums 50 and 55 than it travels around the drums 36 and 37.

Inasmuch as the drum 50 will be rotated at the same speed as is the drum 55, the tendency will be for the drum 55 to draw the thread upwardly from the drum 36 and over the drum 50 at a speed slightly greater than the speed at which the thread travels around the drums 36 and 37, and in this way the thread will be stretched. In actual practice it has been found that there is a slight slippage in the initial loops of thread around the drums 50 and 55 after which, the length of the thread having been substantially increased, the remaining loops of the thread will travel around the drums 50 and 55 with the same tautness. It has also been found that the stretching of the thread in the manner herein described also serves to compress the projecting fibres of the thread down onto the body thereof, as the thread passes around the drums.

It is desirable that the thread in the dryer be smoothed so as to impart a linen-like finish thereto. Any suitable means may be employed for this purpose, such for instance as the ironing devices 62 mounted in pockets 63 of the dryer, which devices have fingers 64 through which the thread passes, as shown in Figure 2.

The spool 56 is mounted on a spindle 65 carried by a bracket 66 pivotally mounted on the end bar 14 of the frame.

Obviously, the spool 56 may be rotated in any suitable manner so that it will take up the thread from the dryer 51. As shown, the spindle 61 has a pulley 67 mounted thereon, which pulley is connected to a pulley 68 carried by the spool 56, by a belt 69.

The bracket 66 may be retained in a fixed position by means of an arm 70 fixed to the side bar 11 and engaging one of the sides of the bracket, in the manner shown by Figure 1.

For the purpose of laying the thread evenly on the spool 56, use is made of a slotted arm 71, which is carried by a rod 72, slidably mounted in brackets 73 and 74. The rod 72 is reciprocated by a cam 75, mounted in the bracket 74. The cam is adapted to be driven from the gear 42, by a spur gear 76 carried by a bearing 77 fixed to the side bar 12, the hub of the gear 76 having a worm 78 meshing with a worm gear 79 on one end of a counter

shaft 80. The opposite end of the shaft 80 has a worm 81 which meshes with a worm gear 82 on the shaft of the cam 75. The construction should be such that one revolution of the cam will move the arm 71 forward and backward over the spool, as will be readily understood.

It is of advantage in machines of the type herein described to provide means for automatically arresting the operation when imperfections appear in the thread, so that the imperfections can be removed before the thread is finished. By the present invention, the drum 36 is connected to the shaft 39 through a clutch 83. This clutch is normally engaged with the drum and it is adapted to be disengaged therefrom, either automatically or manually, by mechanisms to be hereinafter fully described.

The clutch 83 is slidably mounted on the shaft 39, being keyed to the shaft, as indicated at 84. The periphery of the clutch is bevelled, as at 85, and this surface is adapted to engage with a correspondingly bevelled face 86 formed in the end of the drum 36. The clutch is recessed to receive an expandable coil spring 87 which encircles the shaft 39 and bears against the ends of the drum and the clutch to force the latter away from the former.

For the purpose of retaining the clutch 83 in operative engagement with the end of the drum 36, I have provided means, including a lever 88 which is fulcrumed in a bracket 89 carried by the side bar 11. The end of the lever adjacent to its fulcrum point is bifurcated, as indicated at 90, to provide two arms for straddling the shaft 39. These arms of the lever are so formed that the ends thereof bear against a thrust bearing 91 on the outer portion of the clutch 83 and force the clutch inwardly towards the drum (see Figure 6).

The end of the drum 36 adjacent the clutch 83 is encircled by a band 92 composed of two semi-circular sections pivotally supported by a bracket 93. The bracket 93 is carried by a rod 94 supported in the frame. The free ends of the sections of the band 92 are provided with beveled faces 95, and beyond these faces, the extremities of each of the sections of the band are formed with oppositely projecting bosses 96, which are disposed transversely of the band, such bosses being formed with alined openings through which bolts 97, or the like, are passed. Springs 98 are mounted on each of these bolts, in the manner shown by Figure 7, so that the free ends of the band 92 will be drawn together to cause the band to frictionally engage the periphery of the end of the drum, and thus prevent rotation of the drum.

However, inasmuch as the drum should be normally free to rotate, the lever 88 is pro-

- vided with a laterally extending lug 99 having upper and lower beveled faces 100 for engaging with the faces 95 of the band 92. In this way the lug 99 constitutes a wedge 5 for spreading the sections of the band apart under tension of the springs 98, and the construction of the parts should be such that when the clutch 83 is engaged with the drum, the lug 99 will be so disposed between the 10 ends of the band 92 as to force the sections of the band from the periphery of the drum, in the manner clearly shown by Figure 6, and when the lever is actuated to disconnect the clutch 83 from the drum, the lug 99 will 15 be moved inwardly towards the drum a sufficient distance to permit the springs 98 to draw the sections of the band 92 tightly against the drum so as to restrain further movement thereof.
- 20 The end of the lever 88 opposite to the end 90 thereof is adapted to be releasably connected to a detector member, in the form of a lever 101 fulcrumed in a bracket 102 carried by the side bar 12. The outer end of the lever 88 has a socket member 103 adjustably mounted therein, while the bracket 102 is provided with an ear 104 carrying a similarly formed socket-member 105, also adjustably mounted therein. The members 103 and 105 25 are disposed in alinement with each other when the lever 88 is in normal position, so as to receive and retain an annular head 106 on the end of the short arm of the lever 101 (see Figures 6 and 8).
- 30 The lever 101 is pivotally mounted to swing vertically, while the lever 88 is adapted to be swung in a plane at right angles thereto, or horizontally. As shown in Figure 7, the pivotal mounting of the lever 101 includes tension means comprising a coil spring 107 35 adapted to force the end of the long arm of the lever upwardly. The outer end of the long arm of the lever 101 is provided with an eye 108 through which the thread 19 passes.
- 40 The disposition of the eye 108 should be such that it is directly beneath the cross bar 21, and the opening in this eye should be of such size as to ordinarily permit the passage of the thread, but prevent the passage of knots 45 or other imperfections in the thread (see Figure 5).
- 45 In this way the eye 108 constitutes means for detecting imperfections in the thread, and a knot or other imperfection in the thread 50 larger than the opening in the eye will, as the thread is being drawn downwardly towards the tank 32, depress the outer end of the lever 101, thereby swinging the head 106 upwardly and thus disengaging the same from the 55 sockets 103 and 105. This action will release the lever 88 and the spring 87 will force the clutch 83 outwardly thus swinging the long arm of the lever towards the drum 36, moving the lug 99 towards the periphery of 60 the drum, thereby permitting the springs 98

to draw the sections of the band 92 into frictional engagement with the periphery of the drum.

The continued rotation of the spool 18 lengthens the loop 25, thus permitting the 70 arm 22 and roller 24 to descend, thereby applying the band 29 to the disk 28, in the manner heretofore described, and in this way further rotation of the spool 18 will be prevented.

Inasmuch as the drum 55 is driven from the shaft 39, as soon as the clutch 83 has been disconnected from the drum 36, the drum 55 will also stop, and in this way further travel of the thread through the machine will be 80 prevented until the levers 88 and 101 are reset to the operative position shown in Figure 6.

The lever 88, above the socket piece 103, is provided with a handle 109, which may be 85 used to manually disconnect the lever 88 from the lever 101, and which may also be used to re-engage the ends of the levers 88 and 101 with the latch provided by the sockets 103 and 105 and the head 106.

The foregoing description is directed solely towards the construction illustrated, but I desire it to be understood that I reserve the privilege of resorting to all the mechanical changes to which the device is susceptible, 95 the invention being defined and limited only by the terms of the appended claims.

The invention claimed is:—

1. In a thread-treating machine, a thread supply package, a thread take-up spool, 100 thread feeding mechanism, a feeler arm intermediate the supply and feeding mechanism for detecting imperfections in the thread, said feeding mechanism having a brake normally inoperative and a clutch normally operative, and a single lever supported in operative position by said feeler arm affected by the movement of said detector to apply the said brake and disconnect the said clutch.

2. In a thread-treating machine, a thread supply package, a thread take-up spool, thread feeding mechanism, a feeler arm pivotally mounted intermediate the supply and feeding mechanism for detecting imperfections in the thread, said thread supply package having a brake, said feeding mechanism having a brake normally inoperative and a clutch normally operative, and means affected by the engagement of an enlargement 120 in said thread with said feeler arm for simultaneously applying both of the said brakes and disconnecting the said clutch.

3. In a thread-treating mechanism, a thread supply package, a thread take-up 125 spool, thread feeding mechanism, a feeler arm pivotally mounted intermediate the supply and feeding mechanism for detecting imperfections in the thread, said thread feeding mechanism including a drum, means for 130

rotating the drum, a clutch for disconnecting the drum from the said rotating means, a brake adapted to frictionally engage said drum when said clutch is disconnected therefrom, a single lever arranged to control action of both said clutch and the said brake, and means whereby the engagement of an enlargement in said thread with said feeler arm actuates said lever to disconnect the clutch from said drum and to apply the brake thereto.

4. A stop-motion for thread finishing machines, including a pair of levers arranged with adjoining ends detachably locked together, one of the said levers being mounted to swing in a horizontal plane to control the driving mechanism of the machine, and the other lever being mounted to swing in a vertical plane, said second lever having a free end carrying means for detecting imperfections in the thread and when operated by such imperfection is caused to release said first lever to affect the operation of the machine.

25 5. A stop motion for thread finishing machines comprising a drive mechanism and a brake, a single lever controlling the action of said drive, a tripper for said drive control lever, a detector lever controlling said tripper, whereby a passing imperfection in the travelling thread is caused to move the detector lever to trip and release said drive control lever to disconnect the drive and apply the brake by a single movement thereof.

35 6. In a thread-treating mechanism, a thread supply package, a thread take-up spool, thread feeding mechanism, means intermediate the supply and feeding mechanism for detecting imperfections in the thread, said thread feeding mechanism including a thread-carrying drum, means for rotating the drum, a clutch for disconnecting the drum from the said rotating means, a pivoted drum-drive control lever, a pivoted 45 feeler lever, the control lever being retained in operative position by contact with said feeler lever, whereby the passage of an obstruction in the thread moves the feeler lever to release the control lever permitting the 50 clutch to move and stop the machine.

7. In a thread-treating machine, a thread supply package, a thread take-up spool, thread-feeding mechanism between said supply and take-up, clutch control means for 55 said mechanism, spring means normally urging said clutch control means to inoperative position, a feeler arm positioned to be actuated by an imperfection in the thread, and a lock device on said arm normally holding said 60 clutch control means in operative position, whereby actuation of said feeler arm by a thread imperfection moves the lock device to release the clutch control means.

In testimony whereof I affix my signature.
